UNITED STATES PATENT OFFICE.

EDGAR M. FUNK, OF WYTHEVILLE, VIRGINIA.

SINGLE-TRIGGER DOUBLE-BARREL GUN.

No. 893,839.

Specification of Letters Patent. Patented July 21, 1908.

Application filed March 23, 1907. Serial No. 364,132.

To all whom it may concern:

Be it known that I, EDGAR M. FUNK, a citizen of the United States, residing at Wytheville, in the county of Wythe and State of Virginia, have invented a new and useful Single-Trigger Double-Barrel Gun, of which the following is a specification.

This invention relates to single trigger mechanism for double barrel guns.

10 One object of the invention is to provide a mechanism of simple character which may be readily shifted for the purpose of discharging the right and left barrels in the order named, or the left and right barrels consecutively.

15 A further object of the invention is to provide a mechanism of such construction as to prevent the possibility of involuntary discharge of the second barrel from the 20 recoil or rebound due to the discharge of the first barrel.

25 A still further object of the invention is to provide a mechanism of simple character in which all of the parts are carried by the frame of the gun being free from the trigger or other movable parts, so that 30 greater stability and strength is insured.

With these and other objects in view, as will more fully hereinafter appear, the invention consists in certain novel features of 35 construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

40 In the accompanying drawings:—Figure 1 is a sectional elevation of a portion of the frame and breech block of a gun, illustrating a single trigger mechanism constructed in accordance with the invention. Fig. 2 45 is a sectional plan view of the same, the parts being adjusted to position for firing the right barrel in advance of the left barrel.

50 Fig. 3 is a transverse sectional view on the line 3—3 of Fig. 2. Fig. 4 is a view similar to Fig. 2, illustrating the parts adjusted for firing the left and right barrels in the order named. Fig. 5 is a detail perspective view of the mechanism detached. Fig. 6 is a longitudinal sectional elevation illustrating a slight modification of the invention. Fig. 7 is a plan view of the same

partly in section. Fig. 8 is a transverse sectional view on the line 8—8 of Fig. 7. Fig. 9 is a sectional view illustrating a still further modification of the invention. Fig. 10 is a rear elevation of parts of the mechanism shown in Fig. 9. Figs. 11 and 12 are detail views illustrating a means for positively holding the sear engaging lever in elevated position until after the trigger has been fully released.

Similar numerals of reference are employed to indicate corresponding parts throughout the several figures of the drawings.

70 In the firearm shown in the drawing, the breech block A, hammers B, B', and sears C, C' are of any ordinary construction and are operated in the usual manner. The frame D is of the usual type and is provided with a 75 pivot e for a trigger E which may be of ordinary construction, the trigger being preferably mounted at a point midway of the width of the frame.

At the rear face of the breech block are arranged bearings 10 for the reception of a transversely disposed arbor or shaft 11 on which are mounted two sleeves 12 and 13, each of which may rock independently of the other. Projecting forwardly from the sleeves 12 and 13 are rocker arms 14 and 15, respectively, these being arranged in such position that they will be engaged by the hammers B, B' as the latter are cocked, the rocker arms being moved downward against the action of a torsion spring 17. The sleeves are further provided with approximately vertical cam arms 18 and 19, the rear faces of which are engaged by the outturned ends of said spring 17. The spring is formed of a single piece of 95 wire having a central loop that projects within a recess in the breech block, the ends of the wire being thence coiled around the shaft 11 and having outwardly bent terminals that engage with the arms 18, 19, as described.

100 Extending transversely of the lower frame plate is a plate 20 that is provided with slots 21 through which extend guiding studs in the form of screws 22 that pass into threaded 105 openings in the frame plate, these studs serving to guide the plate 20 as the latter is shifted between the two positions shown in Figs. 2 and 4, and the extent of the shifting movement being determined by the engagement of the end walls of the slots with the studs. The opposite ends of the plate 20 are

provided with upturned ears 23 from which project screws or studs 24 that extend through openings 25 formed in the side walls of the frame, but do not project beyond the outer faces of said side walls. These studs are so arranged that by the employment of any small tool, stick, or the like, the plate 20 may be shifted from the position shown in Fig. 2 to that illustrated in Fig. 4, or vice versa, or the studs, if necessary, may be arranged to project beyond the side walls of the frame in convenient position to be manipulated by the fingers.

The plate 20 is provided with a pair of locking notches 26 arranged to be engaged by a small spring 27 that is secured to the lower frame plate by a screw 28. When the plate is shifted from one position to the other, the spring will engage in one or other of the depressions and will lock said plate in its adjusted position.

The plate 20 carries a screw or stud 29 on which is pivoted a lever 30, said lever having a rearwardly extended arm 31 that is reduced in thickness in order that it may form a spring, and at the rear end of the arm is an enlarged head 32 which may be moved under either of the sears C, C' as shown in Figs. 2 and 4, while the lower face of the arm will at all times remain in operative relation to the trigger, so that when the latter is pulled, the arm will be forced up and one or other of the sears will be moved to hammer releasing position. When pressure on the trigger is relieved, the resiliency of the arm 31 will carry it down to initial position.

At the forward end of the lever 30 is a cam 34 having oppositely inclined or pointed faces which are arranged to be engaged by the cam arms 18 and 19, one or other of the arms acting on the cam 34 to shift the position of the lever 30, and the active arm being determined by the position of the plate 20, so that when in the position shown in Fig. 2 the cocking of both hammers will result in downward movement of the rocker arms 14, 15, and rearward movement of the cam arms 18, 19, but the arm 18 only will act on the cam 34, and will shift the rear end of the lever 30 to the position shown in Fig. 2. Should the parts be adjusted to the position shown in Fig. 4 where the left barrel is to be discharged first, the cocking of both hammers will operate as before to depress both rocker arms 14, 15 and move both cam arms 18 and 19 rearward, and in this case the arm 19 alone will act on the cam 34 and will shift the lever 30 to the position shown in Fig. 4, so that in this case the left barrel will be discharged first.

Secured to the lower frame plate is a pair of springs 38 and 39 which are arranged to engage the lever 30 at a point to the rear of the pivot stud 29. When the parts are adjusted to the position shown in Fig. 2 the

spring 38 alone is active, and the spring 39 does not come into play. When adjusted to the position shown in Fig. 4, the spring 39 is active and the spring 38 is idle.

In the operation of the parts as thus far described, reference being now had to Figs. 1, 2 and 3, a pull on the trigger E will raise the lever 30 and the head 32 will be moved upward against the sear C pushing the latter to hammer releasing position and effecting the discharge of the right barrel. This is accomplished against the resistance offered by the spring arm 31, and so long as the pull on the trigger continues, the lever 30 will be frictionally held between the trigger and the lower face of the sear. As the trigger pull is released, either voluntarily or involuntarily on the recoil or rebound, the spring arm 31 will follow the downward movement of the trigger and will bear against the latter with sufficient force to prevent movement of the lever to the left under the influence of the spring 38, this frictional binding of the lever serving to prevent such abrupt shifting as would bring it immediately to a position under the left hand sear, and in case of involuntary pulling of the trigger due to the rebound of the trigger against the finger, or to contraction of the muscles, the frictional grip between the trigger and the arm will simply be increased to an extent proportionate to the degree of pressure exerted on the trigger, and it is not until the trigger is fully released and the arm allowed to move down that the spring 38 can act to throw the lever over to a position under the left hand sear C'. A second pull of the trigger moves the lever upward and results in discharge of the left barrel. On the usual cocking movement, both hammers are thrown back and will engage with the arms 14, 15. Both sleeves 12 and 13 will be rocked and both arms 18, 19 will be thrown rearward. At this time the rear end of the lever 30 is under the left hand sear and as the parts otherwise are in the position shown in Fig. 2 the cam arm 18 will act on the cam 34 and the lever 30 will be turned to the position shown in Fig. 2 against the resistance offered by the spring 38 in readiness for a second operation.

Should the plate 20 have been shifted to the position shown in Fig. 4, the operation will be exactly the reverse of that stated, the lever being first actuated to discharge the left barrel, and then moving over to a position under the right hand sear and on cocking movement the cam arm 19 would act to restore the lever to a position under the left hand sear.

In the modified construction shown in Figs. 6, 7 and 8, the shaft 11' carries two loose cam wheels 18' and 19', these being acted upon by torsion springs 17' that tend to turn them in the direction indicated by the arrow in Fig. 6. Projecting from each of the

disks is a pin 42, the pins being disposed in the path of movement of the rear faces of the hammers, so that when the latter are cocked, the cam disks will be turned in a direction opposite to that indicated by the arrows. The lower frame plate has guides 43 for the reception of a slide bar or plate 20' on which is mounted a pivot stud 29' carrying a lever 30', the rear arm of the lever being reduced in thickness to form a spring of the character previously set forth, and the extreme rear end of the lever forming an enlarged head 32' that is arranged to extend between the sears and the upper portion of the trigger, the latter in this instance being provided with a protruding top piece 44. The front end of the lever is in the form of an upwardly extending arm 34' which is arranged to be engaged by the cam face of the disks 18', 19', and the lever proper is actuated upon by two springs 33' 39' in the manner previously described.

In the drawing, the mechanism is shown as adjusted for the firing of the right and left barrels in the order named and both hammers are shown cocked. If the trigger is pulled the rear end of the lever 30' will be raised and the right hand sear will be moved to release position allowing the hammer to spring forward to firing position. This permits the cam disk 18' to rotate and the face of the cam leaves the upwardly extending arm 34' of the lever, whereupon the spring 38' shifts said lever to a position under the left hand sear, so that on the second trigger pull the left barrel will be discharged. In this case, also, it is to be observed that the resiliency of the upwardly extending arm 34' retains the same in contact with the trigger with sufficient friction to prevent any abrupt movement under the influence of the spring 38', until the trigger has been fully released. When both hammers are recocked, the cam 18' alone will be actuated and will restore the lever to the initial position shown in Fig. 6. By adjusting the plate or bar 20' to the left, the left barrel may be fired in advance of the right barrel, as will be obvious.

Perhaps the most simple embodiment of the invention is that shown in Figs. 9 and 10, wherein the lever 30' is mounted on a transversely movable plate or bar 20', the rear arm of the lever being resilient, and being rocked to move between the sears and the upper face of the trigger in the same manner as shown in Figs. 6 and 7. The forward end of the lever is provided with a double cam head 46 which is arranged to be engaged by two cams 47 and 48 that are carried on the inner faces of the levers. In the position shown in Figs. 9 and 10 the right barrel may be fired first, and as the hammer B springs forward the cam 47 will be moved out of engagement with the lever 46, permitting the spring 38' to shift the lever to a position under the left hand

sear. After the left barrel has been fired, the recocking of both hammers will again bring the cam 47 into engagement with the cam head 46 and the lever will be restored to the initial position shown in Fig. 8. By shifting the position of the carrying plate or bar 20' the operation may be reversed and the left barrel fired in advance of the right barrel.

In order to guard against the possibility of accidental discharge due to recoil or rebound of the gun, or convulsive movement of the finger, a positive lock 60 may be employed, this lock being in the form of a dog that is pivoted to the frame and is urged by a spring 61 from the position shown in Fig. 11 to that shown in Fig. 12 when the trigger is pulled. It will be observed that at the completion of the firing movement, the dog 60 will pass under the sear actuating lever and will maintain the same in elevated position, some play of the trigger being allowed, but before the dog can be released it is necessary for the trigger to move fully down, and the rear end of the trigger head must engage with a rounded cam 62 on the forward face of the dog in order to force the latter to release position, so that the trigger must be fully released before the lever is allowed to descend and shift into engagement with the second sear.

I claim:

1. In a single trigger mechanism for double barrel guns, a trigger, a sear actuating lever adapted to oscillate from one sear to another so as to cause the lifting of one sear in advance of the other, a support on which the lever is mounted, said support being bodily shiftable transversely of the frame so as to determine the order of firing.

2. In a single trigger mechanism for double barrel guns, a trigger, a pivotally mounted sear actuating lever adapted to automatically oscillate from one sear to the other, a support on which the lever is mounted, said support being bodily shiftable transversely of the frame and independently of the trigger and adapted to change the order of firing.

3. In a single trigger mechanism for double barrel guns, a trigger, a pair of sears, a sear actuating lever, and means for automatically oscillating the lever from one sear to the other, a support on which the lever is pivotally mounted, said support being bodily shiftable transversely of the frame and adapted when so shifted to change the fulcrum point of the lever and the order of firing.

4. In a single trigger double barrel gun, a pair of cams under the control of the hammers, a lever, the forward end of which is engageable by said cams when the hammers are cocked, a shiftable fulcrum for said lever, a rearwardly projecting arm forming a part of the lever and normally in position between the trigger and one of the sears, and means for shifting the position of said arm between

the trigger and the other sear after the firing movement of the first hammer.

5. In a single trigger mechanism for double barrel guns, a pair of sears, a pair of hammer controlled cams, a lever arranged to be operated by said cams, said lever having a rearwardly projecting arm arranged to extend under one of the sears, and means for automatically shifting the lever to the opposite sear after the first firing movement, a support on which the lever is fulcrumed, said support being bodily shiftable with the lever and adapted to present the latter into operative relation with either sear.

10 6. In a single trigger double barrel gun, a pair of hammer controlled cams, a pivotally mounted lever with which said cams engage when cocked, said lever having a rearwardly extended arm normally fitting between the trigger and one of the sears, a support in which said lever is fulcrumed, said support being shiftable with the lever to present the latter into operative relation with either sear, and a spring for moving said arm into position between the trigger and the other sear after the firing movement of the first hammer.

15 7. In a single trigger double barrel gun, a pair of hammer controlled cams, a transversely adjustable plate or bar, a lever carried thereby and with which the cams engage, a rearwardly extended arm forming a part of the lever and normally in position between the trigger and one of the sears, and a spring for moving said arm between the trigger and the other sear after the firing movement of the first hammer.

20 8. In a single trigger double barrel gun, a

shaft having bearings to the rear of the breech block, a pair of sleeves fulcrumed on the shaft, rocker arms projecting forward from the sleeves and arranged to be engaged by the levers, cam arms depending from said heads, a spring tending to move the arms against the hammers, a transversely adjustable plate carried by the frame of the gun, a lever fulcrumed to said plate and having a cam head arranged to be engaged by the cam levers, a rearwardly extending arm forming a part of said lever and normally fitting between the trigger and one of the sears, a pair of springs arranged to engage said arms and shift the same to a position between the trigger and the other sear after the firing movement of the first hammer, one of said springs being active when the plate is adjusted to one position and the other being active when the plate is adjusted to the other position.

25 9. In a single trigger double barrel gun, a trigger, a laterally shiftable resilient member for transmitting movement from the trigger to the sears, said member being held frictionally against the trigger by its own resiliency, and means for shifting said member into operative relation with said sears, the force exerted by said shifting means being insufficient to overcome the friction and move said member until the trigger is fully released.

30 In testimony that I claim the foregoing as my own, I have hereto affixed my signature in the presence of two witnesses.
